UNITED STATES PATENT OFFICE.

WILLIAM B. HERRING, OF SCANLON, LOUISIANA.

CONDIMENT-HOLDER.

1,097,717.

Specification of Letters Patent. Patented May 26, 1914.

Application filed April 5, 1913. Serial No. 759,178.

To all whom it may concern:

Be it known that I, WILLIAM B. HERRING, a citizen of the United States, residing at Scanlon, in the parish of Tangipahoa and State of Louisiana, have invented certain new and useful Improvements in Condiment-Holders, of which the following is a specification.

This invention relates to condiment holders and is particularly adapted for dispensing salt and pepper the object being to provide a device of this character which consists of a plurality of compartments and wherein the contents of one may be dispensed while the contents of the other or others as the case may be, will be retained therein through a simple and efficient means which is arranged in the cap.

Other objects as well as the nature, characteristic features and scope of my invention will be more readily understood from the following description taken in connection with the accompanying drawings and pointed out in the claims forming a part of this specification wherein:

Figure 1 is a side elevation of my improved device showing one of the perforated caps through which the contents is dispensed; Fig. 2 is a vertical sectional view taken on the line $x-x$ of Fig. 1; Fig. 3 is a detail plan view of the valve member; and Fig. 4 is a detail plan view of the baffle member.

In the drawings the numeral 5 indicates the body portion of my improved device which is of a substantially cylindrical shape and is composed of metal or any other suitable material and is preferably tapered toward the base 5², being provided with a partition 6 arranged therein and externally 40 screw threaded nipples 7 formed on the side thereof.

A cap 8 is provided which has an internal screw thread so as to be threaded on the nipple 7 and has a series of perforations 9 suitably arranged in the top thereof. A disk shaped valve member 10 is secured to said top through the medium of a rivet or any other suitable means having a plurality of slots 11 formed therein and a stud 12 carried 50 on the one side thereof. A baffle 13 which is preferably of a conical shape is concentrically arranged in the cap 8 and is secured by the same fastening means as the valve member 10, to the top thereof. When it is 55 desired to dispense the contents of one of the compartments the slots 11 of the valve mem-

ber 10 are turned, through the medium of the stud 12 which extends through an arcuate recess 14 on the cap 8, into alignment with the perforations 9 of the cap. It is obvious therefore that while the contents of one of the compartments is being dispensed that the contents of the other compartment will be retained to a certain extent therein, when the holder is vibrated in the usual manner, through the medium of the baffle member 13, as the holder is tilted in a diagonal or horizontal position while the contents thereof is being dispensed. It will also be obvious that when the compartments are to be filled the cap 8 is threaded from the nipple 7 and the desired species of condiment poured through the opening.

It will be understood that the above description and accompanying drawings comprehend only the general and preferred embodiment of my invention and that various minor changes in details of construction, proportion and arrangement of the parts may be made within the scope of the appended claims and without sacrificing any of the advantages of my invention.

Having thus fully described my invention what I claim as new and desire to secure by Letters Patent is:

1. A condiment holder in combination with a receptacle comprising a plurality of compartments each of which is provided with an opening, a perforated cap detachably mounted over each of said openings, and a baffle in connection with said cap, said baffle comprising a single sheet of metal bent into a substantially conical configuration and having its point of securement at the apex thereof for the purpose specified.

2. A condiment holder including a receptacle comprising a plurality of compartments each of which is provided with a lateral outlet opening in proximity to the top of the receptacle, a perforated cap detachably mounted over each of said outlets, and a cone-shaped baffle movably associated with each of said caps having the apex thereof lying adjacent the cap and the enlarged end communicating with the interior of the compartment whereby the adhering of the condiment crossing through the cap is eliminated.

3. A condiment holder including a receptacle comprising a plurality of compartments each of which is provided with an externally screw-threaded nipple through

which access is obtained to the interior of the respective compartments, the usual perforated cap being detachably mounted on each of said nipples, and a cone-shaped baffle movably associated with each of said caps, the outer periphery of the enlarged end of the cone being in spaced relation to the inner periphery of the nipple to allow for the pas-

sage of condiments thereby and through said perforated cap. ¹⁰

In testimony whereof I affix my signature in presence of two witnesses.

WILLIAM B. HERRING.
